UNITED STATES PATENT OFFICE.

PETER H. SCHLEGEL, OF KILLBUCK, OHIO.

RAIL-JOINT.

No. 890,182.

Specification of Letters Patent.

Patented June 9, 1908.

Application filed September 5, 1907. Serial No. 391,516.

To all whom it may concern:

Be it known that I, PETER H. SCHLEGEL, citizen of the United States, residing at Killbuck, in the county of Holmes and State of Ohio, have invented certain new and useful 5 Improvements in Rail-Joints, of which the following is a specification.

The object of the present invention is to provide an improved rail joint which will 10 form a rigid support for the rail ends and which is so constructed as to hold them against any lateral displacement.

To this end the invention consists essentially of a chair formed in two sections which 15 bear against opposite sides of the rail ends and are connected in a peculiar manner so that they can be forced into close engagement with the rails and any looseness readily taken up.

20 For a full description of the invention and the merits thereof and also to acquire a knowledge of the details of construction of the means for effecting the result, reference is to be had to the following description and 25 accompanying drawings, in which:

Figure 1 is a top plan view of the rail joint; Fig. 2 is a transverse vertical sectional view; Fig. 3 is an end view of one of the chair sections. Fig. 4 is a similar view of the opposite 30 chair section. Fig. 5 is a top plan view of the chair section shown in Fig. 3; Fig. 6 is a side elevation of the same. Fig. 7 is a top plan view of the opposite chair section shown in Fig. 4.

35 Corresponding and like parts are referred to in the following description and indicated in all the views of the drawings by the same reference characters.

The numeral 1 designates the two rail ends 40 which are of the conventional type and are preferably formed without the usual bolt holes, since no bolts are required by the present device. A base plate 2 fits beneath the basal flanges of the rails and is provided 45 along one side with an upwardly projecting wing 3 which bears against one side of the two rail ends, and is preferably constructed, as shown in the drawings, so as to fit against the web of the rails between the head and 50 base thereof. The major portion of the base 2 coming beneath the rails is cut away for the reception of the base plate 4 of the opposite section of the chair. A wing 5 similar 55 to the wing 3 projects upwardly from the base plate 4 and bears against the opposite side of the rails. At each end of the base

plate 2 there is formed a transverse slot 6, and the ends of the slots 6 communicate with longitudinal slots 7 which are arranged at an angle with respect to the axis of the rails 60 and are designed to have a cam action as will be hereinafter more fully described. Lugs 8 project downwardly from each end of the base plate 4 of the opposite section of the chair, and these lugs are arranged at an angle 65 corresponding to that of the slots 7 within which they fit.

In applying the chair to a rail joint, the two sections of the chair are brought together with the lugs 8 fitting within the 70 transverse slots 6 in the base plate 2. The two sections are then pushed inwardly against the opposite sides of the rails until the lugs 8 are brought into alinement with the longitudinal slots 7. By sliding the 75 base 4 along upon the base plate 2, the inclined sides of the lugs 8 and slots 7 can be brought into engagement with each other and the two wings 3 and 5 drawn closely against the opposite sides of the rails. In 80 order to lock the two sections of the chair rigidly in position with relation to each other, a series of spike openings 9 are provided in the overlapping portions of the plates at each end thereof. These openings 85 are so arranged with relation to each other that when the lugs 8 have just entered the slots 7, the openings 10 in the two plates will register, and by driving spikes through these openings 10, the two sections of the 90 chair will be held against relative longitudinal movement. The remaining two openings 11 and 12 in each of the series 9 are formed so that the openings 11 will register when the lugs 8 are at intermediate points 95 in the slots 7, and so that the openings 12 will register when the lugs have reached the ends of the slots.

When the joint is first made, it will usually be sufficient to employ the corresponding openings 10, but should a tighter joint be required, or should it be required to take up any looseness in the joint after a certain amount of use, the desired result can be readily obtained by withdrawing the spikes 100 from the openings 10 and replacing them in either the openings 11 or 12, after the base 4 has been moved the required amount, and the two sections of the chair drawn closely against the rails. The edge of the base 105 plate 2 is also provided with a series of longitudinal slots 13 which are arranged at an

angle corresponding to the slots 7. The upper plate 4 is formed with the bolt openings 14 which may be employed if necessary in connection with the slots 13 for crowding the 5 wings tightly against the rails. Attention is directed to the fact that with this joint, no bolt holes are required in the rails, and also to the fact that the chair can be applied to the rails at an intermediate point and can, 10 therefore, be employed for repairing broken rails. The joint also has the advantage of holding the two rail ends rigidly against any relative vertical movement, so that a practically continuous tread portion is provided 15 for the wheels of the rolling stock.

Having thus described the invention, what is claimed as new is:

1. A chair for rail joints comprising a pair of complementary sections each provided with 20 rail engaging means, one of the sections being formed with a cam slot while the opposite section carries a lug received within the cam slot to admit of the rail engaging means being brought into a close contact with the rails 25 when the chair sections are moved with respect to each other, the said sections being provided with overlapping portions having openings therein arranged to register at successive positions of the sections, and fastening members adapted to coöperate with the 30 openings to lock the sections against movement.
2. In a rail joint, the combination of the rails, a chair section comprising a base plate 35 fitting along the rails and provided with a wing bearing against one side of the rails, the said base plate being formed with a longitudinal slot arranged at an angle with respect to the axis of the rails, a second chair section 40 comprising a base plate fitting against the first mentioned base plate and provided with

a wing bearing against the opposite side of the rails, the second mentioned base plate being formed with a lug which coöperates with the before mentioned slot to draw the 45 wings closely against opposite sides of the rails, the overlapping portions of the two plates being provided with a series of openings so arranged as to register at successive 50 positions of the two plates as one of them is moved with respect to the opposite one, and fastening members passed through the registering openings.

3. In a rail joint, the combination of rails, a chair section comprising a base plate 55 formed with a wing which bears against one side of the rails and provided with a longitudinal slot arranged at an angle with respect to the axis of the rails, a second chair section comprising a second base plate fitting against 60 the first mentioned base plate and formed with a wing bearing against the opposite side of the rails, the second mentioned base plate being provided with a lug which coöperates with the slot to draw the wings closely against 65 opposite sides of the rails, one of the overlapping portions of the two base plates being formed with slots arranged at an angle corresponding to the angle of the first mentioned slots, while the opposite base plate is 70 provided with openings corresponding to the second mentioned slots, fastening members passing through the openings and the slots, and means for holding the two chair sections 75 against relative longitudinal movement.

In testimony whereof I affix my signature in presence of two witnesses.

PETER H. SCHLEGEL. [L. S.]
